COMBINATION KEY CHAIN AND POCKET FLASHLIGHT OR SIMILAR ARTICLE

Sidney Schwartz, New York, N. Y., assignor to Bantam-Lite, Inc., New York, N. Y., a corporation of New York

Application June 12, 1952, Serial No. 20,146

Term of patent 14 years

(Cl. D48—24)

To all whom it may concern:

Be it known that I, Sidney Schwartz, a citizen of the United States and resident of New York, in the county of New York, State of New York, have invented a new, original, and ornamental Design for a Combination Key Chain and Pocket Flashlight or Similar Article, of which the following is a specification, reference being had to the accompanying drawing, forming a part thereof, and in which

Fig. 1 is a perspective view showing the top, front and one side of a combination key chain and pocket flashlight embodying my new design, with the cover in open position.

Fig. 2 is a perspective view showing the top, rear and the other side of my design, with the cover in closed position.

Fig. 3 is a top plan view of the flashlight shown in Fig 2, and
Fig. 4 is a bottom view thereof with the chain in a displaced position.

I claim:

The ornamental design for a combination key chain and pocket flashlight or similar article, as shown.
